UNITED STATES PATENT OFFICE.

WILLIAM A. WHITE, OF PHELPS, NEW YORK.

DESIGN FOR A FASTENER FOR HARNESS-NETS.

SPECIFICATION forming part of Design No. 83,107, dated August 21, 1900.

Application filed June 29, 1900. Serial No. 22,081. Term of patent 14 years.

To all whom it may concern:

Be it known that I, WILLIAM A. WHITE, a citizen of the United States, residing at Phelps, in the county of Ontario, in the State of New York, have invented and produced a new and original Design for a Fastener for Harness-Nets, of which the following is a specification, reference being had to the accompanying drawings, forming a part thereof.

Figures 1 and 2 are respectively top plan and side elevation of my fastener.

In the drawings the leading or material feature of my design consists of a fastener for harness-nets having the bars A and B arranged as seen in Fig. 2, having their intermediate portions looped at *a* and *b* in opposite directions, and having substantially-flat opposite ends arranged in close relation to each other, said bars being united at one end and the opposite end of the bar B terminating in a hook-shaped extremity *c*.

The bars A and B, when viewed in plan, as seen in Fig. 1, present the appearance of a rectangular parallelogram.

The bars A and B, having intermediate opposing loops *a* and *b*, the substantially-flat opposite ends of the bars A and B, and the hook *c* together form a simple, characteristic, and pleasing design.

What I claim as new, and desire to secure by Letters Patent, is—

The design for a fastener for harness-nets substantially as herein shown and described.

In witness whereof I have hereunto set my hand this 4th day of April, 1900.

WILLIAM A. WHITE.
